TABLE KNIFE

Irving Harper, New York, N. Y., assignor to Chas. D. Briddell, Inc., Crisfield, Md., a corporation of Maryland

Application October 8, 1954, Serial No. 32,604

Term of patent 14 years

(Cl. D22—3)

To all whom it may concern:

Be it known that I, Irving Harper, a citizen of the United States, residing at New York, in the county of New York and State of New York, have invented a new, original, and ornamental Design for a Table Knife, of which the following is a specification, reference being had to the accompanying drawing, forming part thereof.

Figure 1 is a side elevation of my new design for a table knife.

Figure 2 is a plan view of the table knife shown in Figure 1.

Figure 3 is a cross-sectional view taken on line 3—3 of Figure 1.

I claim:

The ornamental design for a table knife, as shown.
